UNITED STATES PATENT OFFICE.

ARTHUR E. SEARLES, OF HOUSTON, TEXAS, ASSIGNOR TO FREDERICK PARKER.

DISTRIBUTOR FOR COTTON.

Application filed August 30, 1920. Serial No. 406,973.

To all whom it may concern:

Be it known that I, ARTHUR E. SEARLES, a citizen of the United States, residing at Houston, in the county of Harris and State 5 of Texas, have invented certain new and useful Improvements in Distributors for Cotton, of which the following is a specification.

This invention relates to new and useful improvements in a distributor for cotton or 10 other fibrous material, and has particular relation to a machine adapted to be used in the manufacture of mattresses.

One object of the invention is to provide a machine of the character described which 15 has been specially constructed for the purpose of distributing lint cotton or other similar fibrous material onto a table or platform, in a uniform mass, as a preliminary step in the formation or construction of a mattress.

20 Another object of the invention resides in the provision of a fibre distributing machine which will distribute the fibre on a receiving platform or table in such a manner that the center of the bat when deposited will 25 contain somewhat more material than the ends, this for the reason that it is desirable in the construction of mattresses from fibrous material to form the center of the mattress somewhat more compact than the ends.

30 Another object of the invention is to provide a device of the character described from which the cotton bat can be readily removed for insertion into the mattress cover.

A further feature resides in the provision 35 of a device of the character described which is very simple of construction and operation and which may consequently be cheaply manufactured and easily kept in repair.

With the above and other objects in the 40 view the invention has particular relation to certain novel features of construction, operation and arrangement of parts, an example of which is given in this specification and illustrated in the accompanying drawings, 45 wherein:—

Figure 1 is a side elevation of the machine, showing the near wall partially broken away, and

Figure 2 is a front elevation thereof.

50 Referring now more particularly to the drawings wherein like numerals of reference designate similar parts in each of the figures, the numeral 1 refers to a receiving platform or table mounted upon which there is a box-like chute 2, which is sustained upon the table by means of the corner braces or legs

3. The lower sections of the respective walls of this chute are formed into shutters 4, which are hinged to the upper sections by means of the hinges 5 so that they may be 60 readily opened. The chute 2 is fixed in position by being secured to a framework 6. Entering the top of the chute there is an inlet spout 7, whose free end 8 is turned downwardly into vertical position, and pivoted to said downwardly turned end there is an oscillating distributor 9. Lint cotton is discharged by air pressure through the spout 7 and passes through said distributor 9 and is by it deposited on the table 1 underneath. This distributor is oblong in form and its sides 10, 10, are curved outwardly being arcuate in cross section. A pulley 11 is rotatably mounted upon a stub shaft 12 carried by the side of the chute 2 and this 65 pulley is driven by a suitable belt 13. A link 14 is provided, one end of which is pivoted to the pulley 11, eccentrically, and the other end of which is connected to one end of the distributor 9. It is obvious that as the pulley 11 rotates it will operate through the link 14 to oscillate the distributor into the extreme positions shown in dotted lines in Figure 1, and the lint cotton or other fibrous material delivered through said distributor 70 75 80 85 will fall down upon the table 1, and will be distributed from end to end thereof in a soft, fluffy mass or bat. On account of the arcuate sides of the distributor, when it is in either extreme position, the fibre will be retarded somewhat in it, but when in direct vertical position, the fibre will be delivered through it without retardation, and therefore slightly more material will be delivered 90 at the center of the bat than at the ends, so 95 that when the bat is compressed and formed into a mattress the center of the mattress will be somewhat firmer than the ends thereof. After a sufficient quantity of material has been delivered onto the table 1, the shutters 4 are opened and the material is then compressed, by any of the well known processes, and inserted into the mattress cover.

What I claim is:—

1. In a device of the character described, 105 an inlet spout, an oscillating distributor arranged to receive cotton from said spout, and discharge the same in a wide bat and whose sides are arcuate, and means for oscillating said distributor.

2. In a device of the character described 110 an inlet spout, an oscillating distributor

formed with a wide discharge opening and arranged to receive cotton from said spout and deliver the same in a wide bat in successive layers, the sides of said distributor being arcuate, and thereby operating to retard the delivery of said cotton when the distributor is in either extreme position, and means for oscillating said distributor.

3. In a device for distributing cotton, an inlet spout whose discharge end is downwardly turned, an oscillating distributor depending from the downturned end of the spout and formed with a long transverse discharge opening and arranged to receive cot-

ton from said spout and deliver the same in a wide bat, the sides of said distributor being arcuate thereby operating to retard the delivery of said cotton when the distributor is in either extreme position, and means for oscillating the distributor.

In testimony whereof I have signed my name to this specification in the presence of two subscribing witnesses.

ARTHUR E. SEARLES.
